UNITED STATES PATENT OFFICE.

DAVID V. HOCHSTETLER, OF WHITE CLOUD, MICHIGAN.

DEVICE FOR OPERATING SWITCH-POINTS.

1,088,342.

Specification of Letters Patent.

Patented Feb. 24, 1914.

Application filed May 20, 1913. Serial No. 768,866.

To all whom it may concern:

Be it known that I, DAVID V. HOCHSTETLER, a citizen of the United States, residing at White Cloud, in the county of Newaygo, 5 State of Michigan, have invented certain new and useful Improvements in Devices for Operating Switch-Points; and I do hereby declare the following to be a full, clear, and exact description of the invention, such as will enable others skilled in 10 the art to which it appertains to make and use the same.

This invention relates to improvements in devices for operating switch points from 15 a platform of a moving car, and has for its object to so construct a device of this character that the motorman can operate the switch point when the car is some distance therefrom.

20 A further object of the invention is to provide a novel arrangement of levers and links for swinging the switch points in advance of a moving car.

With these and other objects in view, this 25 invention resides in the novel features of construction, formation, combination and arrangement of parts to be hereinafter more fully described, claimed and illustrated in the accompanying drawing, in which:—

30 Figure 1 is a top plan view of the device. Fig. 2 is a vertical sectional view through a portion of a car showing the trip shaft carried thereby in the act of shifting the switch point. Fig. 3 is a sectional view on line 3—3 of Fig. 1. Fig. 4 is a detail perspective view of one end of one of the shifting links. Fig. 5 is a perspective view of one of the trip shaft bearings. Fig. 6 is a sectional view on line 6—6 of Fig. 2.

40 Referring to the drawing, the numerals 1 and 2 designate the main rails of the track, and 3 and 4 the rails of the switch tracks, the latter having pivotally connected thereto the switch point 5. Mounted between the rails is a block 6, preferably formed from cement. Pivotally supported by the block 6 is a lever 7 which is adapted 45 to be rocked by the moving car in a manner to be hereinafter described. A second block 8 is mounted between the main rails, and at a point near the switch point 5 and has pivotally connected thereto a bell crank lever 9, the arm 10 of which is connected to the switch point 5 by a link 11, while the 50 arm 12 thereof is connected to the lever 7 by link 13.

55

Mounted adjacent the main rails 1 and 2 are spaced pins 14 and 15, respectively, which serve as guides for the free ends of the links 16 and 17, the other ends of which are pivotally connected to the ends of the lever 7. The free ends of the links 16 and 17 are provided with outwardly inclined sections 18 and 19, respectively, said sections being adapted for movement between 60 their respective guide pins 14 and 15 so that sections 18 and 19, respectively, said sections, when pressure is brought to bear thereagainst by the trip shafts 21, will force the same toward the guide pins alternately, 65 during which time the engaged head will during its forward movement also move laterally, thereby permitting the trip shaft engaged therewith to disengage the same.

Both platforms of the car 22 are provided 70 with a pair of spaced bearings 23, which support the spring pressed trip shafts 21, hereinbefore mentioned.

Any suitable covering may be placed over the operative parts of the device to protect 80 the same from rain, sleet or snow.

From this construction it will be seen that when it is desired to shift the switch point 5 so that the car can pass upon the switch rails 3 and 4, it is only necessary for the 85 motorman to force the trip shaft 21 which is mounted upon the right hand side of the platform so that the lower end thereof will contact with the head 20 carried by the inclined section 18 of the link 16, whereupon 90 further movement of the car forwardly will cause said link to rock the lever 7 until the trip pin disengages the head, which is readily accomplished owing to the lateral movement imparted to the section 18 by the 95 guide pins 14, which operation causes the link 13 to move, thus shifting the bell crank lever so that the switch point 5 is swung in contact with the main rail 2 through the medium of the link 11. It is obvious that a 100 following car to continue on the main track will require the operation of the link 17, which will reverse the movement of the device so that the switch point 5 will be shifted from contact with the rail 2.

105 What is claimed is:—

1. In combination with a switch point, of a bell crank lever, a link connecting the lever and switch point, a lever pivotally connected to the bell crank by a link, guide pins, links having one of their ends connected to the opposite ends of the lever, and their other ends 110

operating between the guide pins, and means carried by a car for alternately engaging the last named links to shift the lever and bell crank lever, and thus the switch point.

- 5 2. In combination with the main rails and the switch rails, of a switch point pivotally connected to one of the switch rails, a lever pivotally mounted between the main rails, a bell crank lever mounted between the rails
10 and adjacent the switch point, links pivotally connecting the lever and bell crank and the bell crank and switch point, spaced guide pins mounted adjacent the main rails, links

having one of their ends pivotally connected to the outer ends of said lever and their other ends provided with inclined sections terminating in lateral heads, and means carried by a car for alternately engaging said heads to force the same forwardly and laterally, as and for the purpose set forth. 15 20

In testimony whereof, I affix my signature, in the presence of two witnesses.

DAVID V. HOCHSTETLER.
